UNITED STATES PATENT OFFICE

JOHN M. SHIELDS, OF CHICAGO, ILLINOIS, ASSIGNOR TO F. H. NOBLE & CO., OF CHICAGO, ILLINOIS, A CORPORATION OF ILLINOIS

DESIGN FOR A JEWELRY CONTAINER

Application filed June 20, 1929. Serial No. 31,772. Term of patent 14 years.

To all whom it may concern:

Be it known that I, JOHN M. SHIELDS, a citizen of the United States, residing at Chicago, in the county of Cook and State of Illinois, have invented a new, original, and ornamental Design for a Jewelry Container, of which the following is a specification, reference being had to the accompanying drawing, forming a part hereof, wherein—

Figure 1 is a view in perspective, showing my new design, embodied in a box suitable for the reception of jewelry, watches, or other small ornamental articles; and

I claim:

The ornamental design for a jewelry container, as shown.

JOHN M. SHIELDS.
